UNITED STATES PATENT OFFICE.

JOHN MAGEE, OF DETROIT, MICHIGAN, ASSIGNOR TO DIAMOND POWER SPECIALTY COMPANY, OF DETROIT, MICHIGAN, A CORPORATION OF MICHIGAN.

SOOT-CLEANER FOR WATER-TUBE BOILERS.

1,160,306.

Specification of Letters Patent. Patented Nov. 16, 1915.

Application filed March 4, 1915. Serial No. 12,075.

To all whom it may concern:

Be it known that I, JOHN MAGEE, a citizen of the United States of America, residing at Detroit, in the county of Wayne and State 5 of Michigan, have invented certain new and useful Improvements in Soot-Cleaners for Water-Tube Boilers, of which the following is a specification, reference being had therein to the accompanying drawings.

10 This invention relates to soot-cleaners for water tube boilers and to an arrangement thereof that is particularly adapted for a type of upright water tube boilers in one section of which, a lower main drum and an 15 upper main drum are connected by water tubes that are substantially upright and are arranged in sets that are separated by baffles so that the gases of combustion from a fire or furnace chamber at one side of the setting 20 which surrounds the boiler, pass longitudinally up and down and along the water tubes and finally escape from a smoke opening at the upper side removed from the gas inlet.

25 The invention includes means not only for cleaning the tubes which are in the hotter spaces of the boiler by means that can be readily withdrawn out of the action of the highly heated gases of combustion, but also 30 means permanently installed in the passes more remote from the combustion chamber and hence cooler, the cleaning being accomplished in such manner that the deposited products of combustion such as soot, light 35 ash and the like are readily dislodged from the water tube and also the baffles and interior surfaces of the boiler which are in contact with the gases.

40 The invention consists in the matters hereinafter set forth, and particularly pointed out in the appended claims.

In the drawings, Figure 1 is a view in upright longitudinal section of a boiler of the type hereinbefore described, equipped 45 with a blower that embodies features of the invention; Fig. 2 is a view in detail showing a blower unit adaptable for the hotter portions or passes of the boiler; Figs. 3 and 4 are detail views showing a blower support 50 clamp.

Referring to the drawings, a lower drum 1 and upper drum 2, mounted in a suitable setting 3, are connected by a middle or central set of water tubes indicated at 4 which

are substantially straight and by outer sets 55 5 and 6, the end portions 7 and 8 of the latter being inturned so as to tap readily into the shells of the drums 1 and 2. A baffle 9, of suitable construction, such as tiling or the like, extends from the lower drum up 60 and along the set 6, the interval between the top of the baffle and the upper drum 2 forming an inlet into a central down pass in which the middle set 4 of the tubes is located, a baffle 10 extending from the upper drum 2 toward the lower drum 1 forming the other wall of this pass. The latter baffle also serves as a division wall between this middle pass and the last or smoke pass of the boiler as the gases pass up along the 70 outer set 5 of the tubes and escape through the top opening 11 of the setting. A suitable furnace, not indicated is located at the lower portion of the setting to one side thereof and the gases of combustion enter 75 through the throat or gas inlet indicated at 12. As the lower portion has the pass in which the set 6 of tubes is extremely hot especially toward the lower portion thereof, a removable blower unit is used. In preferred form this consists of a jet pipe 14 rotatably mounted in a fitting 15 so as to be turned by a suitably connected handle 16 whereby jets may be projected from suitable 80 nipples or openings 17 and end jetting holes 85 18 between and along the tubes 6. Arms maintained in a plane transverse to the tube 6 is thrust between them. Preferably the parts 17 are Venturi because of the increased effect obtained by the use of a Venturi bore 90 in the nozzles. A stem pipe or supply line 19 is connected by a suitable swivel with an upright T 20 having an extension pivot rod 21 that together with the member 25 is journaled on a suitable base plate 22 as 95 in brackets 23 or the like. A horizontal arm 24 from the fitting 20, the outer end of which is braced by a suitable diagonal member 25 carries an upright stem 26 on its outer end on which is swiveled a coupling member 27 that in turn is connected by an elbow 28 and rotatable coupling indicated generally at 29 to the T 15. A valve 30 may be inserted in the arm 100 if desired. The base plate is mounted across a suitable opening in the furnace 105 setting and the arm 14 is thereby swung readily in and out of position and manipulated.

lated by its handle so as to direct it in any desired way across and along the tubes and over the interior smoke surfaces.

A housing 32 is inserted in a suitable opening 5 of the setting 3 of the boiler to form a journal support for a jet pipe 33 that extends through the setting and across the first tube and into the third pass of the boiler. Of course it may be extended entirely across 10 and be supported at the other end in the setting if it is so desired. Suitable jet nozzles 34 on this pipe 33 are arranged to direct jets between the water tubes of the sets in the passes and against the interior smoke surfaces 15 of the boiler. Steam is supplied to the pipe through a suitable fitting 35 that also forms a bracket support. A hand wheel or sprocket wheel 36 and depending chain 37 or the like provide means for conveniently rotating the unit.

Another rotatable unit 38 is likewise inserted in the lower portion of the middle and smoke passes in a suitable bearing member 39 with steam bracket connections 40 25 and manipulating wheel 41. As the unit is directly opposite the portion of the boiler that is taken care of by the retractable jet pipe 14, it does not extend into this pass but terminates in the middle pass. Both the 30 upper blower unit 33 and the lower one 38 may be supported along their length and at the outer end by suitable fittings or hangers indicated at 42, which are clamped or otherwise suitably secured to the water tubes of 35 the boiler. Such clamps preferably consist each of a bearing bar 43 bridging a pair of tubes to which clips 44 secure them with an applied cap 45 embracing the jet pipe and forming a closed bearing therefor. Both 40 the rotatable blowers may be water or air jacketed or otherwise shielded as by an asbestos lined casing from the effect of the gases that pass by them.

As a result of this construction a blower is 45 obtained that is particularly adaptable for this type of boiler as it sweeps and cleans all the water tube surfaces and the interior surfaces of the boiler that are in contact with the gases of combustion and are liable to be 50 coated with deposits therefrom. By the use of the retractable member which is readily accessible and accordingly easily manipulated, the extremely heated portions of the passes are as readily reached as the more 55 accessible and cooler ones. The use of a hand blower is done away with and the boiler is readily kept in order by operation of the blower without withdrawing the boiler from service. Obviously the particular 60 distribution of the baffles and pipes of the boilers may be other than as indicated in the drawings and in such case the blower units are necessarily varied to meet conditions of service.

Obviously, changes in the details of con-

struction may be made without departing from the spirit of my invention and I do not care to limit myself to any particular form or arrangement of parts.

What I claim is:—

1. The combination of a boiler having upright water tubes, divided by baffles whereby the tube space has substantially upright passes through which the gases of combustion pass in opposite direction, with a 75 blower comprising rotatable jetting means certain of which are common to all of the passes and others to some of the passes only and all of which are adapted to direct jets over and along the water tubes and against 80 the interior surfaces of the passes occupied by the tubes, and rotatable jetting means adapted to be projected and retracted out of certain of the tube spaces and to direct cleaning jets along the tubes and between them 85 and in and along the interior surfaces of the pass into which the means is moved.

2. The combination of a boiler having upright water tubes arranged in a setting and baffles dividing the tube space into passes 90 with gas inlet at the lower end of one pair whereby the gases of combustion are led over the tubes in the direction of length thereof, a blower comprising rotatable jet tubes mounted in the setting at intervals from the 95 inlet and extended across the passes for directing jets over and along the tubes and the interior surfaces of the passes, means exterior to the setting for manipulating the tubes, and a bodily retractable and projectable jetting pipe mounted on the exterior of the setting and adapted to be moved into operative relation to the boiler tubes in the pass adjacent the gas inlet for directing jets across and along them and over the interior 100 surfaces of the pass.

3. In a boiler, upright water tubes, a setting incasing the tubes, baffles dividing the tube space into passes whereby the gases of combustion are led up and down the tubes 110 in the direction of length thereof from a gas inlet at the lower end of one pass to a smoke outlet at the upper end of the last pass, a blower comprising a rotatable jet pipe rotatably mounted in the setting and on the 115 water tubes across which it extends transversely through the baffles into all of the passes at a considerable interval above the gas inlet, a jet pipe journaled in the setting and on the water tubes across which it extends transversely in some of the passes remote from the gas inlet, a jet pipe mounted on the exterior of the setting and adapted to be bodily moved into operative relation with the water tubes in a pass adjacent the 120 gas inlet, and means for manually operating the several blower members.

4. In a boiler, a plurality of upright passes with a gas inlet at the lower end of one pass and a smoke outlet at the upper end of the 130

last pass, water tubes arranged therein and longitudinally thereof, a jet pipe common to all the passes, means rotatably mounting the jet pipe transversely to the water tubes a distance from the gas inlet for directing jets along and across the tubes and the interior surfaces of the passes, means for manipulating the jet pipe, a jet pipe common to some of the passes at a distance farther from the 10 gas inlet, means rotatably mounting the pipe on the water tubes transversely thereto for directing jets of steam across and along the pipes and interior surfaces of the passes, means for manipulating the jet pipe, a supply line, a jet pipe, and swiveled connections articulating the jet pipe with the supply line, the jet pipe being thereby bodily movable into operative relation with the water tubes in the first pass, and means for rotating 15 the jet pipe for directing jets across and along the water tubes of the pass and interior surfaces of the latter.

20 5. In a boiler having water tubes and baffles dividing the tube space into passes, a jet pipe for directing jets along and across the tubes in the interior surfaces of the passes, provided with jet-forming members of Venturi bore.

25 6. The combination with a boiler having

upper and lower members connected by sets 30 of substantially upright water tubes, baffles between the sets forming passes for conducting the gases of combustion along the water tubes in the direction of length thereof, and a setting inclosing the tube space having a 35 gas inlet into the first pass and a gas outlet from the upper end of the last pass of rotatable jet pipes secured in openings through the setting and baffles across the water tubes, certain of the pipes being common to all of 40 the passes at points remote from the gas inlet, means for rotatably mounting the pipes in position in the setting and on the water tubes, an articulated supply pipe connection mounted on the exterior of the setting and a 45 jet pipe rotatably secured thereto and adapted to be moved bodily across the first pass above the gas inlet and adjacent thereto into operative relation with the water tubes and interior surfaces thereof, together with means 50 for rotating and controlling the latter jet pipe.

In testimony whereof I affix my signature in presence of two witnesses.

JOHN MAGEE.
